UNITED STATES PATENT OFFICE

GEORGE LISLE BEERS, OF COLLINGSWOOD, NEW JERSEY, ASSIGNOR, BY MESNE ASSIGNMENTS, TO RADIO CORPORATION OF AMERICA, OF NEW YORK, N. Y., A CORPORATION OF DELAWARE

AMPLIFYING SYSTEM

Application filed April 25, 1931. Serial No. 532,753.

My invention relates to amplifying systems and, more particularly, to systems of the type wherein piezo-electric crystals are employed as coupling devices.

5 It is a well-known fact that sections cut from piezo-electrically active materials, such as tourmaline, or quartz, may be utilized for the purpose of selectively coupling one electric circuit to another. When so used, a 10 crystal section, theoretically, should offer relatively high impedance to all frequencies other than its natural frequency of vibration.

In actual practice, however, it has been 15 found that the selectivity of a crystal section departs considerably from the selectivity theoretically attainable. The reason for this is found in the fact that the inter-electrode capacity of the crystal holder offers a path 20 between the coupled circuits, the reactance of which is substantially independent of the crystal section.

It is, of course, possible to neutralize the 25 effect of the inter-electrode capacity by a bridge circuit similar to the circuits used for neutralizing the grid-plate capacity in thermionic tubes. Such circuits, nevertheless, require critical adjustment for best results and their inclusion in factory-made radio receivers requires skilled operatives.

30 It is, accordingly, an object of my invention to provide an amplifying system wherein the full selectivity of a piezo-electric crystal may be utilized.

Another object of my invention is to provide 35 a piezo-electric crystal holder wherein the inter-electrode capacity is compensated.

Another, and more specific, object of my 40 invention is to provide non-critical means for compensating the inter-electrode capacity of a piezo-electric crystal holder.

The foregoing objects, in a preferred embodiment of my invention, are attained by so re-locating the electrodes, between which the detrimental capacity exists, with respect to 45 the crystal section, that a grounded electrostatic shield may be interposed between them.

The novel features that I consider characteristic 50 of my invention are set forth with particularity in the appended claims. The invention in its entirety, together with ad-

ditional objects and advantages thereof, will best be understood from the following description of a specific embodiment, when read in connection with the accompanying drawing.

The single figure of the drawing is a view, 55 partly perspective and partly diagrammatic, of a portion of an amplifying system including a preferred embodiment of my invention.

The apparatus illustrated in the drawing includes a thermionic tube 1, hereinafter referred to as a source of alternating potential, and a second thermionic tube 3, herein-after referred to as the amplifier. Although 60 thermionic tubes of the three-electrode type are illustrated as the source and amplifier, respectively, my invention is not restricted thereto, it being, of course, applicable to amplifying systems of any desired type. 65

The output electrode 5 of the source and the input electrode 7 or grid of the amplifier are coupled through a piezo-electric crystal 9, the dimensions of which are such as to render it resonant to the frequency of the potentials delivered by the said source. The piezo-electric crystal is supported between a pair of flat upper electrodes 11 and 13 that are, respectively, connected to the aforementioned output and input electrodes of the 70 thermionic devices and a third electrode 15, which is so disposed with respect to the said two flat electrodes as to define a crystal receiving space. Preferably, the first mentioned pair of electrodes and the third electrode are mounted upon and carried by a 75 block 17 of insulating material such as porcelain or the like.

A metallic shielding element 19 is vertically supported from the third or lower electrode and is disposed between the free ends of the upper electrodes. The shielding device, preferably, is provided with a cut-away portion 21 so dimensioned as to accommodate the crystal. A ground connection 23 for the 80 shielding device and the lower electrode is provided and ground connections 25 and 27 are also provided for the source and the amplifier. 85

In the operation of the system as disclosed, 100

alternating potentials appearing across the output circuit of the source are impressed between the electrode 11, connected to the plate thereof, and the lower electrode 15 upon which the crystal section rests. Such potentials, if at the frequency to which the crystal section is resonant, cause the said section to vibrate in unison therewith and, by reason of the fact that the crystal, when vibrating, develops potentials across its faces, an electric field appears between the flat electrode 13 connected to the grid of the amplifier and the common lower electrode 15 which is connected to the cathode thereof through ground.

By reason of the fact that the shielding element, which is at ground potential, is interposed between the input and output electrodes 11 and 13 of the crystal holder, it serves to effectively intercept all electric field lines which originate either at the input or the output electrode and thus prevents any transfer of energy between the said electrodes by reason of the capacity existing therebetween. In other words, the only energy which can pass from the source to the amplifier must go by way of the crystal element itself and such energy, accordingly, is restricted to the frequency of the crystal and to frequencies differing therefrom by not more than a few hundred cycles.

My invention, therefore, provides a new and improved coupling device which is vastly more selective than coupling devices known to the prior art. It does not require critical adjustment nor is the adjustment thereof prone to change during use.

Although I have illustrated and described a specific embodiment of my invention, numerous modifications thereof will be apparent to those skilled in the art to which it pertains. My invention, therefore, is not to be limited except insofar as is necessitated by the prior art and by the spirit of the appended claims.

I claim as my invention:

1. In combination, means for producing fluctuating potential, amplifying means, coupling means for impressing potentials from said source on said amplifying means, the coupling means including a piezo-electric crystal and a plurality of electrodes disposed adjacent thereto, and screening means interposed between certain of said electrodes for minimizing the capacitive transfer of energy therebetween.

2. The combination set forth in claim 1 characterized in that certain of the electrodes, between which the capacity is minimized, are disposed adjacent to the same face of the crystal.

3. The combination set forth in claim 1 wherein certain of the electrodes, between which the capacity is minimized, are disposed adjacent to the same face of the crystal, and further characterized in that another of the

electrodes is disposed adjacent the opposite face of the crystal.

4. The combination set forth in claim 1 characterized in that the capacity minimizing means is constituted by an electrostatic shield.

5. The combination set forth in claim 1 wherein the capacity minimizing means is constituted by an electrostatic shield and further characterized in that the said shield is connected to a point the potential of which, in the operation of the system, is lower than that of the electrodes between which the said means is interposed.

6. The combination set forth in claim 1 wherein the capacity minimizing means is constituted by an electrostatic shield and further characterized in that at least one of the plurality of electrodes is electrically connected to the said shield.

7. In an amplifying system, a piezo-electric crystal holder including a plurality of electrodes that define a crystal-receiving space and screening means interposed adjacent said space for minimizing the capacitive transfer of energy between certain of said electrodes.

8. A piezo-electric crystal holder including an input electrode and an output electrode so disposed with respect to a common electrode as to define a crystal-receiving space and screening means for preventing the capacitive transfer of energy between said input and output electrodes.

9. A piezo-electric crystal holder including an input electrode, an output electrode and screening means interposed therebetween.

10. A piezo-electric crystal holder including a pair of electrodes, a third electrode disposed in capacitive relation to said pair of electrodes, and metallic screening means disposed between the electrodes of said pair, said means being electrically connected to the third electrode.

In testimony whereof, I have hereunto subscribed my name this 20th day of April, 1931.

GEORGE LISLE BEERS.
